TONE COMPENSATED VOLUME CONTROL

Leslie F. Curtis, Springfield, Mass., assignor to
 United American Bosch Corporation, Springfield, Mass., a corporation of New York

Application September 11, 1934, Serial No. 743,534

9 Claims. (Cl. 179—1)

This invention relates to a volume control for radio or allied electrical equipments, and more particularly to a tone compensated volume control. It is well known that the response of the ear to the audio frequency band is not proportional at different volume levels. The middle frequencies have an apparent response greater than that of the lower frequencies at the volume level of average home entertainment. To compensate for this non-linear response, the lower frequencies should be reduced in less degree than the remaining frequencies in order to produce an effect of realism at low volume levels.

Therefore one object of the invention is to provide a tone compensated volume control which reduces the middle and higher frequencies proportionately more than the lower frequencies.

A further object is to provide a combined volume and tone control.

Other objects and advantages will in part be stated and in part be apparent when the following specification is read in connection with the drawing in which the figure is a diagrammatic representation of the volume control showing it applied to an audio circuit.

Referring to the drawing more in detail, the numeral 1 represents a vacuum tube comprising the first audio stage of an amplifier. The tube 1 has in the cathode circuit a biasing resistor 2 which is shunted by a bypass condenser 3. The plate potential is fed through a plate coupling resistor 4, and a coupling condenser 5 transmits audio frequencies to the next amplifier stage. A fixed resistance 6 is serially connected with the resistance element R of a volume control potentiometer P, the other end of the resistance element being grounded. For the sake of clarity the resistance element R is divided into a section R' lying above the movable potentiometer arm 7, and a section R'' which lies below the potentiometer arm. A variable tone control resistance 8 has an end connected to the coupling condenser 5 and the other end free. Resistance 8 has a slideable contact 9 which is connected to a tone control condenser 10 which may be variable, although the invention will operate successfully with a fixed condenser. A common shaft may control both the arm 7 and contact 9, but it is not essential to obtain the improved performance of the invention. The other side of condenser 10 is connected to the potentiometer arm 1. The signal is taken from a point between condenser 10 and slideable contact 9 and is led to the input circuit of tube 12 of the second audio stage. Tube 12 also has a biasing resistor

13 in the cathode circuit, shunted by a bypass condenser 14.

As earlier mentioned the human ear does not have a flat response at low volume levels, but favors the middle audio frequencies at the expense of the higher and lower frequencies. If an amplifier has a flat frequency response and reproduces music at the original studio volume level, no compensation is needed. The usual home entertainment level is, however, but a fraction of the studio level and requires bass compensation to achieve naturalism. With a studio level of 60 decibels at 1,000 cycles which is to be reproduced at a level 35 decibels lower, a 100-cycle tone should be reduced only about 17 decibels in order to compensate for the peculiarities of the ear, and to present an effect of realism at the lower level. The differential between the necessary energy level of the 100-cycle and the 1000-cycle tones varies according to the level of reproduction as contrasted with the original studio level. The circuit shown in the drawing may be adjusted to automatically regulate this differential according to the requirements of the different volume levels. In case the maximum output of the amplifier does not equal the studio level, the resistance 6 is inserted into the circuit and has a value determined by the difference between these levels. Thus in most home installations some initial compensation is required even at full volume of the amplifier. With full amplifier volume equal to the studio level, condenser 10 of .006 mfd. and P of 500,000 ohms, it has been found that resistance 8 should vary approximately inversely as the square root of the resistance R'' lying below the potentiometer arm 7, which variation is substantially the same as that in direct proportion to the square root of the ratio between the original, and the reduced volume level at 1000 cycles. This may be expressed mathematically as resistance 8 varies as

$$\frac{1}{\sqrt{R''}}$$

or resistance 8 varies as

$$\sqrt{\frac{E_o}{E_g}}$$

where E_o is the greatest available signal voltage and E_g is the voltage across the input of tube 12. If resistance 8 is fixed, the low frequencies are quickly reduced as the volume is initially lowered, and thereafter they remain constant, independent of any further volume level. This has been the case with prior controls. For re-

production in rooms of different acoustic properties, it may be desirable to have the bass compensation adjustable at will. This is readily accomplished by making the condenser 10 independently variable or adjustable, as shown in Fig. 1. The resistance 8 under this condition is varied proportionally with the potentiometer resistance R exactly as before.

It will be apparent that many changes and 10 modifications may be made in this invention by any one skilled in the art without departing from the scope and true spirit of the invention as defined in the following claims.

What is claimed is:

15 1. In a compensated volume control circuit, an audio source, a potentiometer having a resistance connected across said source, a variable resistance connected in series with said source, a slider arm on said potentiometer, a movable contact on said 20 variable resistance, a condenser connected between said slider arm and said movable contact, and an output connection between said condenser and said movable contact.

2. In a compensated volume control circuit, an 25 audio source, a series circuit comprising a fixed resistance and a potentiometer resistance connected across said source, a variable resistance connected in series with said source, a slider arm on said potentiometer, a movable contact on said 30 variable resistance, a condenser connected between said slider arm and said movable contact, and an output connection between said condenser and said movable contact.

3. In a compensated volume control circuit, an 35 audio source, a potentiometer having a resistance connected across said source, a variable resistance connected in series with said source, a slider arm on said potentiometer, a movable contact on said variable resistance, a variable condenser 40 connected between said slider arm and said movable contact, and an output connection between said condenser and said movable contact.

4. In a compensated volume control circuit, an 45 audio source, a series circuit comprising a fixed resistance and a potentiometer resistance connected across said source, a variable resistance connected in series with said source, a slider arm on said potentiometer, a movable contact on said variable resistance, a variable condenser 50 connected between said slider arm and said movable contact, and an output connection between said condenser and said movable contact.

5. In a compensated volume control circuit, an 55 audio source, a potentiometer having a resistance connected across said source, a variable resistance connected in series with said source, a slider arm

on said potentiometer, a movable contact on said variable resistance, a mechanical drive connection between said slider arm and said movable contact, a condenser electrically connected between said slider arm and said movable contact, and an output connection between said condenser and said movable contact.

6. In a compensated volume control circuit, an audio source, a potentiometer having a resistance connected across said source, a variable resistance connected in series with said source, a slider arm on said potentiometer, a movable contact on said variable resistance, a mechanical drive connection between said slider arm and said movable contact, a variable condenser electrically connected between said slider arm and said movable contact, and an output connection between said condenser and said movable contact.

7. In a compensated volume control circuit, an audio source, a series circuit comprising a fixed resistance and a potentiometer resistance connected across said source, a variable resistance connected in series with said source, a slider arm on said potentiometer, a movable contact on said variable resistance, a mechanical drive connection between said slider arm and said movable contact, a condenser electrically connected between said slider arm and said movable contact, and an output connection between said condenser and said movable contact.

8. In a compensated volume control circuit, an audio source, a series circuit comprising a fixed resistance and a potentiometer resistance connected across said source, a variable resistance connected in series with said source, a slider arm on said potentiometer, a movable contact on said variable resistance, a mechanical drive connection between said slider arm and said movable contact, a variable condenser electrically connected between said slider arm and said movable contact, and an output connection between said condenser and said movable contact.

9. In a compensated volume control circuit, an audio source, a potentiometer having a resistance connected across said source, a variable resistance connected in series with said source, a slider arm on said potentiometer, a movable contact on said variable resistance, a mechanical drive connection between said slider arm and said movable contact, a condenser electrically connected between said slider arm and said movable contact, and an output connection between said condenser and said movable contact.
